[57] CLAIM

The ornamental design for an integrated document scanner and keyboard, as shown and described.

DESCRIPTION

FIG. 1 is a front, left side view of an integrated document scanner and keyboard showing our new design;

FIG. 2 is a rear elevation view thereof;

FIG. 3 is a left side elevation view thereof;

FIG. 4 is a front elevation view thereof;

FIG. 5 is a right side elevation view thereof;

FIG. 6 is a top plan view thereof; and,

FIG. 7 is a bottom plan view thereof.

The broken line showing of environmental structure in the drawings is for illustrative purposes only and forms no part of the claimed design.
